United States Patent Office

Des. 176,303
Patented Dec. 13, 1955

176,303

ADVERTISING DISPLAY

Louis R. Beal and Lester H. Shrader, Sioux Falls, S. Dak.

Application March 1, 1955, Serial No. 34,789

Term of patent 14 years

(Cl. D80—1)

Fig. 1

Fig. 3

Fig. 2

Fig. 6

Fig. 7

Figure 1 is a front elevational view of an advertising display, showing our new design;

Figure 2 is a side elevational view of the advertising display of Figure 1;

Figure 3 is a top plan view of the display of Figures 1 and 2 with parts broken away to show better the construction thereof.

The dominant features of our design reside in the portions shown in full lines.

We claim:

The ornamental design for an advertising display, as shown and described.
